RADIOACTIVE PARTICLE COUNTING

William Bernstein, Middle Island, N. Y., and Robert Ballantine, Baltimore, Md., assignors to the United States of America as represented by the United States Atomic Energy Commission

Application March 20, 1950, Serial No. 150,692

6 Claims. (Cl. 250—83.6)

1

The present invention relates to a method and apparatus for counting particles emitted from a radioactive substance. The accurate counting of radioactive particles presents several difficult problems. These difficulties are inherent in the properties of the particles and consideration of these properties is necessary in the design of the detection instrument.

Alpha particles are absorbed by the walls or window of the usual counter unless a very thin window is used. Thin windows are mechanically difficult to construct and usually let in a large amount of moisture as well as alpha particles. The present method and apparatus eliminates the need for using thin windows.

Beta particles are not emitted from the nucleus with a definite energy but are emitted in a continuous spectrum. The end point of the spectrum corresponds to the maximum energy of the nuclear decay but the particles are distributed with energies down to zero. The method and apparatus of the present invention counts beta particles throughout the entire spectrum with the same high accuracy.

The requirements of any accurate counter are stringent especially with respect to absolute counting. The wall and air absorption paths must be kept as low as possible particularly for low energy particles. Also it is necessary that no portion of a sample be lost in the radioactive source preparation for absolute counting. The sensitive counting volume of the apparatus of the present invention contains the sample whose radioactivity is to be measured. This reduces the wall and air absorption paths to essentially zero. It is also possible with the present invention to collect the radioactive substance to be measured directly in the counter so that no part of the sample can be lost in the preparation for counting. The physical configuration of the collected substance therefore remains the same from the time of its accumulation until after its radioactivity is measured.

It is an object of the present invention to provide an apparatus to count accurately the number of particles emitted from a radioactive substance.

It is another object of the present invention to provide a counter which can be accurately used for either relative or absolute counting.

It is still another object of the present invention to provide a counting apparatus with a very low background count.

It is a further object of the present invention to provide a counter which can be easily dismantled for decontamination purposes.

2

It is still a further object of the present invention to provide a counter which includes means for collecting the substance whose radioactivity is to be measured.

5 Another object of the present invention is to provide a counter which can be built inexpensively and still maintain a high counting accuracy.

Still another object of the present invention is to provide a method for measuring the number of particles emanating from a radioactive substance.

Other objects and advantages will be in part obvious and in part pointed out hereinafter.

More particularly, a preferred embodiment of 15 the apparatus of the present invention comprises two electrodes mounted on a base plate and electrically insulated from one another. A counter envelope which surrounds both electrodes is detachably mounted on the same base plate. The counter envelope contains a support on which 20 the radioactive substance to be measured can be collected. Means are also included for hermetically sealing the counter envelope and for introducing a counting gas into the envelope. Electronic measuring circuits and a source of high 25 potential are connected across the electrodes to provide means for counting the particles and registering the counts.

The many objects and advantages of the present 30 invention may best be appreciated by reference to the accompanying drawings the figures of which illustrate apparatus incorporating a preferred embodiment of the present invention and capable of carrying out the method of the invention. In the drawings:

Figure 1 is an isometric view of a counting apparatus embodying the invention with a portion of the counter wall broken away to show the internal construction. The apparatus is shown in relation to standard electronic amplifying circuits and a mechanical counting register.

Figure 2 is a vertical section of Figure 1 taken through the plane 2—2.

Referring to the drawings, particularly Figure 45 2, it is seen that base plate 10 supports connector 12 on a collar 14. Collar 14 is attached to plate 10 by means of screws 16. Connector 12 is fastened to collar 14 by screws 18. Connector 12 is a standard high voltage electrical connector 50 with a single centrally located terminal 13 (shown only in Figure 1). Soldered to terminal 13 is wire 20 which extends through hole 22 in plate 10. Surrounding wire 20 for part of its length is a tube 24 which is sealed to and insulated from plate 10 by a glass-to-metal seal 26. Welded to wire 20 at point 28 is a thin wire anode 30. The

inclusion of weld 28 within tube 24 shields any sharp points which may be present in the weld and thereby prevents spurious counts and eliminates sparking. Anode 30 terminates in an electrically conductive bead 32 for similar reasons. This bead may be glass with an aquadag coating.

Surrounding anode 30 is the cylindrical cathode of the counter made up of sections 34 and 36. Section 34 is attached to plate 10 by screws 33. Section 36 is of slightly larger diameter than 34 and can slide on over section 34. In the sensitive counting volume 35, beneath tube 24, sections 34 and 36 form a cylinder with anode 30 located along its axis. The purpose of this construction is to facilitate the dismantling of the cathode for decontamination purposes.

Surrounding cathode sections 34 and 36 is counter envelope 40 which is supported by support 42 and gasket 44. Support 42 is attached to set screw 46 which in turn is threaded through yoke 48. The yoke (see Figure 1) is pivotally mounted to plate 10 by screws 50. The volume enclosed by counter envelope 40 may be rendered gas-tight by tightening screw 46 which presses the envelope up against a gasket 52 in plate 10. One end of envelope 40 contains a support 54 for a radioactive substance 56. Support 54 can be solid or it can be porous for filtration purposes. The entire counter assembly can be supported by means of stand 51 (see Figure 1) which is attached to plate 10 by screws 53.

Penetrating collar 14 and plate 10 are inlet and outlet tubes 58 and 60 respectively. Gas may be admitted into the counter envelope from a gas supply 62 through valve 64, bubble meter 66 and inlet tube 58. To regulate the outward flow of air and gas through tube 60 a valve 68 is provided.

To operate the counting apparatus a high voltage supply 70 is connected between the anode and cathode of the counter. The difference of potential between anode 30 and cathode section 36 is provided from supply 70 by means of lead 72, terminal 13, wire 20 to anode 30. The other end of the circuit is completed through lead 74, screw 18 through collar 14 and screw 16 to base plate 10. From base plate 10 the circuit is carried through screw 39, cathode section 34 to cathode section 36.

In order to amplify and register the pulses received at anode 30 during the operation of the counting apparatus, standard electronic components consisting of preamplifier 76, amplifier 78 and counting register 80 are connected to the anode through terminal 13. Preamplifier 76 is used when it is desired to eliminate the effect of cable capacitance between counter anode 30 and amplifier 78. When used in this manner preamplifier 76 is mounted relatively close to terminal 13. Amplifier 78 and register 80 can then be connected to preamplifier 76 by any length of cable necessary.

One preferred embodiment of counter envelope 40 is the sintered glass Gooch crucible which has long been used by chemists in gravimetric analyses. In this embodiment envelope 40 is glass and support 54 is sintered glass. The method and apparatus of the present invention will be described using this embodiment.

Counter envelope 40 may be removed from the counter assembly by loosening screw 46 and swinging aside yoke 48. The crucible can then be used in a standard filtration procedure to accumulate the substance whose radioactivity is to be measured. When the filtration is complete the crucible 40 can be removed from the associ-

ated apparatus, with the radioactive substance 56 collected on sintered support 54, and mounted in gas-tight fashion between gaskets 52 and 44 by means of screw 46 and yoke 48. At this stage the radioactive substance 56 has been introduced into the sensitive volume 35 of the counter without disturbing its physical configuration from the time of its accumulation. In this way there is no danger of losing any of the substance in the transfer process. The radioactive particles emanating from substance 56 are now being emitted into the sensitive counter volume 35.

To obtain the proper counting gas mixture within the counter, valves 64 and 68 are opened. The rate of gas input can be measured on bubble meter 66. The air that is inside the counter envelope will be emitted through outlet tube 60 when valve 68 is open. The proper length of time for flushing the counter in this manner may easily be determined with use.

Operation of the counter will depend on the difference in potential between anode 30 and cathode 36, maintained by high voltage supply 70. In the preferred embodiment a difference in potential of 3800 volts using methane as the gas will cause the counter to operate as a proportional counter. That is, the height of the detected pulse is dependent upon the total ionization caused by the radioactive particle passing through the sensitive counter volume. The field in the immediate vicinity of anode 30 is sufficiently intense to cause secondary ionization yet not enough to cause the discharge to spread throughout the counter.

Because the particles do not have to pass through a window, absorption paths are reduced to essentially zero and extremely low energy particles will produce sufficient ionization to record counting impulses. High energy particles pass completely through the sensitive volume before their energy is lost, and therefore produce a maximum discharge which is limited by the length of the sensitive volume. These factors plus the continuous renewal of the counting gas results in excellent reproducibility of counts over short and long time periods.

The particles ionized by the passage of the radioactive particles are attracted to anode 30 and change the potential of this wire when they arrive. This results in an output pulse appearing at terminal 13 of the connector 12 which pulse is amplified by preamplifier 76, and amplifier 78 and subsequently counted on register 80. The height of the output pulse depends on the amount of the original ionization, the type of gas used and the original difference in potential maintained between anode 30 and cathode 36.

To determine when the proper operation of counting gas has been reached it is merely necessary to note the action of counting register 80. When substantially all the air has been emitted and the counter contains only the counting gas the counts on register 80 will be recorded in a regular manner. In the preferred embodiment using a Gooch crucible as the counter envelope 40 it has been found that the proper proportion of counting gas is obtained after the counter is flushed at the rate of one bubble of counting gas per second for a period of two minutes without prior drying.

The difference in potential between anode 30 and cathode 36 may be lowered so that the counter works as an ionization chamber. This difference in potential can be raised above the Geiger threshold so that the counter operates in

the Geiger region. The gas requirements are such that most any gas can be used for counting in the proportional region. When using gas the counter may be operated at pressures slightly above atmospheric to prevent the diffusion of air into the counter. However, it is not necessary that a counting gas be used at all as tubes 58 and 60 may also be used for evacuating the counter. Using the counter in this way will still maintain the advantages of having the substance emit particles directly into the sensitive counting volume.

The apparatus of the present invention may also be used without the cathode sections 34 and 36. This can be accomplished by making counter envelope 40 of an electrically conductive material. When used this way the substance 56 can be collected on the support 54 and the envelope 40 can be positioned on base plate 10 so that wire anode 30 will be along the axis of the envelope. Electrical connection can easily be made between base plate 10 and envelope 40. In this manner, the envelope 40 will act as the cathode of the radioactive particle counter.

By making envelope 40 of an electrically conductive material is also meant making an envelope that has this material coated on its inner surfaces. The coating when properly connected would then act as the cathode of the counter.

Since many embodiments of the present invention might be made and since many other changes may be made in the preferred embodiment described above it is to be understood that the foregoing description is to be interpreted as illustrative only and not in a limiting sense except as required by the appended claims.

We claim:

1. A separable apparatus for counting radioactive particles which comprises in combination, a base plate, a fixed structure including a first and a second electrode fixedly mounted thereon, said first electrode being positioned axially within said second electrode and electrically insulated therefrom, a support plate adjustably attached to said base plate in spaced relation thereto, a removable counter envelope surrounding said second electrode and detachably affixed to said base plate and to said support plate, a support for a radioactive substance fixedly mounted within said envelope to position said substance adjacent to one end of said first electrode, means for mounting and dismounting said counter envelope between said base plate and said support plate, means for hermetically sealing said counter envelope and means secured to said base plate for introducing and expelling a gas from said counter envelope.

2. Apparatus as recited in claim 1 together with electrical measuring means and a source of high potential, both connected between said first and said second electrode.

3. A separable apparatus for counting radioactive particles which comprises in combination, a fixed structure including a base plate, a first and second electrode fixedly mounted thereon, said first electrode being positioned axially within said second electrode and electrically insulated therefrom, a support plate adjustably attached to said base plate in spaced relation thereto, a removable open-ended counter envelope surrounding said second electrode and detachably affixed to said base plate and to said support plate, a support for a radioactive substance fixedly mounted within said envelope to position said substance adjacent to one end of said first electrode, means for mounting and dismounting said counter envelope

between said base plate and support plate, means for hermetically sealing said counter envelope, means secured to said base plate for introducing and expelling a gas from said counter envelope and electrical measuring means and a source of high potential both connected between said first and said second electrode.

4. A separable apparatus for counting radioactive particles which comprises in combination, a fixed structure including a base plate, a first and second electrode fixedly mounted thereon, said first electrode being positioned axially within said second electrode and electrically insulated therefrom, a support plate adjustably attached to said base plate in spaced relation thereto, a removable open-ended counter envelope surrounding said second electrode and detachably affixed to said base plate and to said support plate, a support for a radioactive substance fixedly mounted within said envelope to position said substance adjacent to one end of said first electrode, said support including a porous filter member suitable for deposition of said substance thereon by filtration, means for mounting and dismounting said counter envelope between said base plate and support plate, means for hermetically sealing said counter envelope, means secured to said base plate for introducing and expelling a gas from said counter envelope and electrical measuring means and a source of high potential both connected between said first and said second electrode.

5. A separable apparatus for counting radioactive particles which comprises in combination, a fixed structure including a base plate, an electrode fixedly mounted thereon, a support plate adjustably attached to said base plate in spaced relation thereto, a removable counter envelope made of an electrically conductive material surrounding said electrode, said envelope being detachably affixed to said base plate and to said support plate and with said electrode positioned axially within said envelope and electrically insulated therefrom, a support for a radioactive substance fixedly mounted within said envelope to position said substance adjacent to one end of said electrode, means for mounting and dismounting said counter envelope between said base plate and said support plate, means for hermetically sealing said counter envelope, means secured to said base plate for introducing and expelling a gas from said counter envelope and electrical measuring means and a source of high potential both connected between said electrode and said counter envelope.

6. A separable apparatus for counting radioactive particles which comprises in combination, a fixed structure including a base plate, an electrode fixedly mounted thereon, a support plate adjustably attached to said base plate in spaced relation thereto, a removable open-ended counter envelope made of an electrically conductive material surrounding said electrode, said envelope being detachably affixed to said base plate and to said support plate and with said electrode positioned axially within said envelope and electrically insulated therefrom, a supporting member for a radioactive substance, said member being fixedly mounted within said envelope to position said substance adjacent to one end of said first electrode and comprising a porous filter upon which said substance may be deposited, means for mounting and dismounting said counter envelope between said base plate and said support plate, means for hermetically sealing said counter envelope

lope; means secured to said base plate for introducing and expelling a gas from said counter envelope and electrical measuring means and a source of high potential both connected between said electrode and said counter envelope.
